(57) CLAIM

The ornamental design for the upper handle portion for carpet extractor, as shown and described.

DESCRIPTION

FIG. 1 is a perspective view of a upper handle portion for carpet extractor showing our new design;

FIG. 2 is a perspective view thereof;

FIG. 3 is a rear elevational view thereof;

FIG. 4 is a left side elevational view thereof;

FIG. 5 is a front elevational view thereof;

FIG. 6 is a right side elevational view thereof;

FIG. 7 is a top plan view thereof; and

FIG. 8 is a bottom plan view thereof; and,

FIG. 9 is a rear perspective view thereof.

The carpet extractor parts shown in broken lines in FIGS. 1 and 9 are shown for illustrative purposes only and form no part of the claimed design.
